UNITED STATES PATENT OFFICE.

JAMES J. LAWLER, OF PELHAM, NEW YORK.

BATH-TUB.

1,079,775.

Specification of Letters Patent. Patented Nov. 25, 1913.

Application filed October 12, 1912. Serial No. 725,377.

To all whom it may concern:

Be it known that I, JAMES J. LAWLER, a citizen of the United States, and resident of Pelham, in the county of Westchester and State of New York, have invented certain new and useful Improvements in Bath-Tubs, of which the following is a specification.

My invention relates to bath tubs, the object being to heat the rim by means of the hot water pipe mounted in close contact with said rim; another object is to provide a filling means of the hot and cold water near the bottom of the tub to avoid splashing.

In the accompanying drawing, Figure 1 is an end elevation on a tub, showing my invention, part of the tub being broken away: Fig. 2 is a plan view of a tub, showing the water connection on one end: Fig. 3 is a fragmental view of a tub showing the arrangement of the pipes, which are shown in front elevation, there being no difference in the connections whether placed on the end of the tub, as in Fig. 2 or on the side, as in Figs. 1 and 3. Fig. 4 shows an enlarged section of the rim and means for holding the hot water pipe as applied to tubs specially constructed to employ my invention, and Fig. 5 is a similar view showing a means for attaching the heating pipe to old tubs or tubs in use.

Like reference numbers indicate similar parts in the several views. Arrows show direction of the water.

The bath tub, 1, is preferably of the "enameled iron ware" type, having the curved rim, 1', on the inner or under side of which the hot water pipe, 2, is placed and held by a series of suitable clamps, 3, fastened to the rim by means of a screw, 4. The hot water pipe connects to the supply pipe, 2', by a coupling, 2'', or otherwise and passes around the tub under the rim to the controlling faucet, 5. The cold water pipe, 6, is coupled to the cold water faucet, 7. I prefer to arrange the pipes as shown, so that

the faucet body, 8, connects with the hot and cold water faucets and with the inlet pipe, 9, which enters the tub a short distance above the bottom, a hood 9' open at the bottom giving direction to the water issuing from the pipe 9. The outlet and overflow pipe 10 is of conventional make.

Such being the description, the operation is as follows: To heat the rim, the hot water faucet is turned on and the water runs through the pipe 2 around the tub, the rim being heated by radiation. The water is discharged near the bottom of the tub without splashing, and if desired to regulate the temperature of the water in the tub, the cold water faucet can be turned on or both faucets regulated to control the supply from either pipe, as usual.

What I claim is—

A device of the class described comprising in combination with a bath tub, an outwardly turned rim thereon provided with two perforations therethrough, a faucet body positioned beneath said rim, a faucet at each end of said faucet body and extending through said perforations, a pipe connecting centrally of said faucet body and adapted for entering the tub, a hot water entrance pipe extending vertically to a point beneath said rim and thence circumferentially of the tub and beneath said rim and connecting with one end of the faucet body in vertical alinement with one of said faucets, and a vertically positioned cold water pipe between said vertical portion of the hot water pipe and said tub entrance pipe and connected to the opposite end of the faucet body in vertical alinement with the other end of said faucet members.

Signed at New York in the county and State of New York this 8th day of October A. D. 1912.

JAMES J. LAWLER.
